RADIATOR CAP FOR AUTOMOBILES

Filed Aug. 9, 1921

Patented Dec. 4, 1928.

1,694,030

UNITED STATES PATENT OFFICE.

LOUIS A. BEAN, OF DENVER, COLORADO.

RADIATOR CAP FOR AUTOMOBILES.

Application filed August 9, 1921. Serial No. 490,918.

The object of this invention is to provide a radiator cap for automobiles which will be not only ornamental, but will be theft-proof as well, may be easily opened for filling the radiator, and will so carry a thermometer as to prevent theft of the latter.

Briefly, the invention consists of an adapter adapted to be mounted upon the neck of the radiator and immovably retained thereon, a cap-body proper which preferably is ornamental and has a limited amount of rotation upon said adapter, and means for controlling access to the interior of said cap. Preferably said means is at the back of the cap and is lock-controlled, and said limited rotation brings the back into position for filling the radiator when said means is removed. Temperature registering means is also mounted on the cap and has its stem projecting therethrough and secured on its inner end. The cap also conveniently carries on each side a mirror so that the driver may see each side of the road in the rear, and lighting means are provided for illuminating the thermometer and ornamenting the cap.

In the drawings wherein one embodiment of the invention is shown,

Fig. 1 is a side elevation of the cap with portions broken away;

Fig. 2 is a rear elevation indicated by line 2-2 of Fig. 1;

Fig. 3 is a partial vertical longitudinal section;

Fig. 4 is a sectional detail taken on line 4-4 of Fig. 3;

Figs. 5 and 6 are similar views of the separate parts of Fig. 4;

Fig. 7 is a sectional detail taken on line 7-7 of Fig. 2 showing the mirror-clamp construction;

Fig. 8 is a sectional detail showing the ornamental lighting feature, being taken on line 8 of Fig. 1; and

Fig. 9 is a sectional detail similar to that of Fig. 4 showing a slightly modified construction.

Fig. 10 is a similar view of a further modification.

The drawings indicate the usual radiator R of an automobile provided with a filling neck N. The cap of the present invention includes an adapter A which may be threaded internally to receive an externally threaded neck as shown in Figs. 3 to 6, or ex-

ternally threaded to receive an internally threaded neck as in Fig. 9. The cap-body 10 is preferably in the form of an ornamental device such as an animal head as shown, the head being normally directed forward and having its rear portion inclined as indicated in Fig. 1 to provide ample clearance for the hood H when the same is lifted and the key K of the lock is removed.

In the form of Figs. 3 to 6, the neck N, which receives the adapter A, is notched on its upper edge at 12, and the adapter is threaded at 14 to receive the base of the cap 10. The upper outer portion of said adapter is provided with an annular groove for receiving a spring ring 15 split as indicated at 16, and the outer intermediate portion of said adapter A is shouldered as indicated at 18 for engagement with the outer face of the base of the cap 10.

The distance between the shoulder 18 and the under face of ring 15 is somewhat less than the thickness of said cap-base so that the cap may be rotated upon the adapter to a limited extent. This amount is preferably one-half revolution so that the back of the device may be directed forward for filling the radiator or gaining access to the interior of the cap. The ring 15 effectually prevents removal of the cap from the adapter. A clip or retainer 20 is adapted to fit in a vertical groove in the inner face of the adapter and to have its lower extremity seat in said notch 12 in the neck N. The upper end of said groove 22 terminates in a notch 24 in the upper edge of adapter A which notch 24 receives an offset tongue 120 of the retainer 20, said tongue 120 overhanging and engaging the ring 15 approximately across its entire width so as to effectually prevent removal thereof. Said retainer 20 is secured in place in the groove 22 and notches 12 and 24 by a set screw 25 which may be easily set by a slender screw driver. Thus removal of the cap 10 from the adapter A and of the adapter from the neck N is easily prevented, while limited rotation of the cap is permitted. Said set screw 25 passes through the retainer 20 and enters a threaded hole 26 in the adapter.

In the form of Fig. 9, where the neck N is internally threaded, the adapter A is externally threaded and a set screw 28 is passed therethrough into engagement with neck N to prevent removal therefrom.

The back of the cap 10 is flat as shown 110

and has a filling aperture adapted to be closed by a plug 30 having a knob or handle 32 for manipulation thereof. As shown this knob is countersunk and is also circular so that it will be impossible to engage the same with a tool for twisting the plug and breaking the lock bar. Preferably said plug 30 is flanged at 34 and snugly fit so as to produce a steam or vapor tight joint. The 10 inner wall of the plug is rounded off as shown and is provided with a projection 35 into the path of which a locking bolt 36 is adapted to be projected through the medium of a key K which controls the tumbler 15 barrel 40 of a lock housing 38 secured in position as by means of headless screws 39 which may be braided over to prevent removal. Thus when the bolt 36 is projected the plug 30 can not be removed, but when 20 withdrawn said plug may be readily removed with one's fingers which will enter the depression around the knob 32.

A thermometer 42 of any desired type having a stem adapted to pass through the 25 cap 10 may be secured in said cap so as to prevent removal through the medium of suitable locking means such as lock nuts 44 secured to said stem on the inside of the cap. Packing 45 may be employed to secure 30 a vapor tight joint. The thermometer may be illuminated at night by means of a globe 46 having a reflector 48 and connected to an electric conductor 50. The conductor 50, which may enter through the rear wall of 35 the cap 10 also leads to ornamental lights 51 which serve as the eyes in the animal's head.

Suitable supports, such as arrow shafts 52, extend laterally and upward from the cap 40 and carry mirrors 54 having rims 55 provided with ears 56 clamped between ears 58 on bands 60 mounted upon the shafts 52. By adjusting the bands 60 and the joints between ears 56 and 58, the mirrors 54 may 45 be located as desired to show the road in the rear on both sides.

In assembling the construction of Figs. 3 and 4, the adapter A will be placed on the neck N and the cap 10 threaded onto the adapter. The ring 15 will then be passed through the opening in the back of the cap and sprung into position in the groove in the upper end of the adapter. The parts will be adjusted to aline the groove 22 with 55 the notch 12, and the retainer 20 placed therein, the screw 25 being set through said opening with a long screw driver or the like. The locking means for the thermometer, indicated at 44, is also readily applied through 60 said opening. In the form of Fig. 9, the screw 28 is set before the cap 10 is applied to the adapter.

In Fig. 10 a form is shown wherein the tongue 120 is omitted, this form otherwise 65 being like that of Figs. 3 and 4. Here the

retainer 20 and the set screw 25 are placed before the cap 10 is applied to the adapter, the retainer serving only to prevent rotation of the adapter on the radiator neck. However, the tongue 120 of said Figs. 3 and 4 70 is of value particularly in the event that ring 15 should snap and fall out of its groove, which otherwise probably would permit removal of the cap from the adapter.

When the device is in normal position it 75 will be directed forward as seen in Fig. 1. When it is desired to fill the radiator or gain access to the interior of the cap for any other purpose, the cap is rotated one-half revolution, as above indicated, the bolt 80 36 is withdrawn by key K, and the plug 30 removed by rotation. The mirrors 54 are readily adjustable by swinging the frame 55 and ears 56 on the ears 58 and twisting the bands 60 on the shafts 52, the position of 85 these parts being maintained by tightening the pivoting bolt 62 which passes through said ears. At night the thermometer and the eyes of the animal are illuminated as above mentioned. 90

I claim:

1. A radiator cap comprising an adapter to be secured to a radiator neck, a cap body secured upon said adapter and having a limited amount of movement only thereon, 95 said cap-body having an opening therein for access to the interior thereof, and a closure for said opening, said cap body being movable by reason of said limited amount of movement to position where said opening is 100 readily accessible.

2. A radiator cap comprising an adapter to be secured to a radiator neck, a cap body rotatably mounted on said adapter, retaining means for said body to permit limited rotation thereof and prevent removal thereof 105 from said adapter, said body having an opening therein for access to the interior thereof, and a lock-controlled closure for said opening. 110

3. A radiator cap comprising an adapter to be secured to a radiator neck, means on the adapter to anchor the same on said neck, a cap body rotatably mounted on said adapter with the adapter projecting into the 115 interior of said body, the projecting end of said adapter having a groove therein and a ring in said groove projecting therefrom to prevent removal of said body.

4. A radiator cap comprising a cap body having means to anchor the same on a radiator neck, an opening being provided in said body for access to the interior thereof and to said anchoring means, a rotatable closure therefor, and lock-controlled means to prevent rotation of said closure. 120

5. A radiator cap comprising a cap body having means adapted to anchor said body on a radiator neck and accessible only from the interior of the body, said body having 130

an opening therein, a closure rotatable into said opening and having a projection, and a lock-controlled bolt movable into the path of said projection to prevent rotation and removal of said closure.

5 6. In a radiator cap, a cap body having means for locking the same on a radiator neck and accessible only from the interior of said body, said body having an opening for 10 access to the interior thereof, and a lock-controlled closure for said opening.

7. A radiator cap comprising an adapter to be secured to a radiator neck and locked thereon, a cap body locked upon said adapter 15 and having a limited amount of movement only thereon, the locking means for said parts being accessible only from the interior of the cap body, said body having an opening for access into said interior, and a lock-controlled closure for said opening.

8. A radiator cap comprising a cap body adapted to be rotatably mounted on a radiator neck, retaining means for said body to permit limited rotation thereof with respect 20 to the neck and to prevent removal, said 25

body having an opening for access to the interior thereof, and a lock-controlled closure for said opening.

9. A device of the class described embodying therein a radiator filler spout, an adapter 30 having an opening therethrough and being telescopically interfitted with said spout, radially adjustable means accessible through the opening for securing the adapter to the spout, a cap secured to the adapter and closing the opening therein, and a theft-proof lock associated with said cap and preventing access to said adjustable means.

10. A device of the class described embodying therein a radiator filler spout, an 40 adapter having an opening therethrough and being telescopically interfitted with said spout, screw means accessible through the opening for securing the adapter to the spout, a cap secured to the adapter and closing the opening therein, and a theft-proof lock associated with said cap and preventing access to said screw means.

In testimony whereof I affix my signature.
LOUIS A. BEAN.
